UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FEELER TIP.

Application filed February 2, 1925. Serial No. 6,292.

To all whom it may concern:

Be it known that I, HARRY A. DAVIS, a citizen of the United States, and a resident of Hopedale, in the county of Worcester 5 and State of Massachusetts, have invented an Improvement in Feeler Tips, of which the following description, in connection with the accompanying drawings, is a specification, like characters on the drawings 10 representing like parts.

This invention relates to filling feelers for looms and more particularly to the tip of such feelers.

It is now the common practice to provide filling feelers with a toothed filling engaging end or tip and in some cases the teeth have been formed transversely of the feeler in a diagonal direction, while in others the teeth have been formed straight 15 across the filling end of the feeler. The purpose of such teeth is to hold the filling feeler from premature movement along the filling carrier to call for a change of filling. Since the same loom may have different 20 kinds or characters of filling used therein at different times, it is desirable that the same feeler may have filling engaging teeth which are suitable for cooperation with the different kinds of filling employed in the 25 loom. For instance, when the filling is of coarse count and loosely spun, the teeth of the feeler tip may be of one character or construction to properly cooperate therewith, whereas, when the filling is of finer 30 count or of harder twisted yarn the teeth of the feeler should be of a different character or construction.

One of the important features of the present invention, therefore, is to provide the 40 feeler with a tip which shall have along its filling engaging portion a series of teeth which differ from each other in their construction, so that one series of such teeth may properly cooperate with one kind or 45 character of filling and another series of teeth may cooperate with a different kind or character of filling, so that regardless of the kind or character of the filling employed, the same feeler may be utilized effectively 50 in cooperation therewith.

In accordance with one feature of the present invention, the feeler tip is provided with a plurality of horizontal rows of teeth wherein the individual teeth of one row are 55 staggered relative to the individual teeth

of an adjacent row. Thus the teeth of the different rows may be of different kind or construction, that is, the teeth of one row may be more blunt or more rounded than the teeth of another row, or the teeth of the 60 various rows may be so contrasted in construction as to cooperate with any kind or character of filling employed. The staggered relation of the individual teeth is advantageously utilized to produce an angular effect of the teeth, either one way or the other, and the holding surface thus presented to the filling is of a broken nature, affording greater gripping effect.

The invention and the various novel features thereof may best be made clear from the following description and the accompanying drawings of one good form thereof.

In the drawings:

Fig. 1 is a perspective view of a feeler 75 having a tip constructed in accordance with the present invention;

Fig. 2 is a perspective end view enlarged of the feeler tip and showing more particularly the teeth of the several rows formed 80 of different gage;

Fig. 3 is an end elevation of the feeler tip shown in Fig. 2;

Fig. 4 is an end elevation of the feeler tip showing a slightly modified form there- 85 of;

Fig. 5 is a similar view of still another modification; and

Fig. 6 is an end view and a further modification of a feeler tip and teeth arrangement.

The feeler may be of usual construction and as shown is of the side swipe type similar in this respect to the feeler now employed in certain feeler mechanisms.

The feeler 1 as shown has a bridge portion 2 and side wing portions 3, while a frontwardly extending stem portion 4 is utilized for supporting a spring, not shown, which normally acts, as usual, to hold the 100 feeler in its rearward feeling position. The parts so far described may be of usual construction.

The feeler 1 has a filling engaging or tip portion provided with a series of filling engaging teeth, the teeth of the series being arranged, as shown, diagonally of the feeler tip. The feeler tip is preferably formed of non-metallic material, such as fibroid or the like, and is made up of two or more parts,

each of which has a series of horizontal teeth formed thereon. These parts are secured to the feeler 1 so that the projecting teeth offer a filling engaging and holding device for engagement with the filling on detecting beats.

In the form of the invention herein shown, the end portion 5 of the feeler 1 has a slot 6 extending transversely thereof in a horizontal direction, the word "horizontal" being used, of course, in the sense that when the feeler is in operative position, the slot normally assumes a substantially horizontal position.

15 The feeler tip is shown in the present instance as formed of three separate parts, 7, 8 and 9, each of which may be formed of the same or different material, and one of these parts, 7 in the present instance, has a portion 10 which extends into the slot 6 of the feeler end 5 and is there secured by means of a bolt 11. Each of the other members of the feeler tip has an engaging shoulder 12 which lies against the end portion 13 of the feeler end, and these parts or members, 8 and 9, are secured to the central member 7 by means of bolts 14 which are passed through the three members. This manner of mounting the several members of the feeler tip upon the feeler end is a convenient and good practical form of the present invention, but in its broader aspect the invention is not necessarily limited to these details.

35 Each of the feeler members 7, 8 and 9 is provided with a series of teeth, as indicated in the several figures of the drawing, and when the several members of the feeler tip are secured together, the teeth are arranged in a checker-board or staggered relation, as indicated.

40 As indicated in Fig. 2, the teeth 15 formed in the upper member 9 of the feeler tip are relatively large, that is, their filling engaging surface 16 is more blunt than the corresponding surfaces of the teeth of the other members of the feeler tip. The teeth 17 on the center member 7 of the feeler tip are of less width than the teeth 15, that is, they are of a different gage, while the teeth 50 18 of the lower member 8 of the feeler tip are yet of smaller width or different gage than the teeth 17 of the central member. Not only are the teeth 15, 17 and 18 of different gage, but the individual teeth of each horizontal row of teeth are staggered relative to the teeth of an adjacent row, the effect being that the teeth of the several rows are adapted to co-act with and function properly in cooperation with the different kinds or characters of filling. For instance, if the filling is of very coarse and large character, the larger and more blunt teeth 15 of the upper member of the feeler tip may appropriately function to hold the feeler from side slipping movement, where-

as, if the filling be of somewhat finer count or harder twisted, the teeth 17 of the central portion of the feeler tip may function effectively, while if the yarn be of still finer count and hard twisted, the smaller gage 70 teeth 18 may effectively function to prevent premature side swipe movement of the feeler.

With the separate teeth of the individual rows of teeth arranged in staggered relation, the filling engaging surface is of course broken transversely, that is, in a vertical direction of the feeler tip, thus offering a greater gripping effect upon the filling.

75 In Fig. 3 the different gages of the filling engaging teeth shown by Fig. 2 are more clearly illustrated.

80 In the modification shown by Fig. 4, the series of teeth 19 of the upper member of the feeler tip and the lower horizontal series 85 of teeth 20 of the lower member of the feeler tip are of substantially the same gage, whereas, the intermediate series 21 of the central member of the feeler tip are of finer gage than either.

90 In the modification shown by Fig. 5, the reverse arrangement from that effected in Fig. 2 is illustrated, that is, the lower teeth 22 of the lower member of the feeler tip are of larger gage than the intermediate row 95 of feeler teeth 23, while the upper row 24 of the feeler teeth are of still smaller gage.

95 In the modification shown in Fig. 6, the teeth 25 of each of the horizontal rows of teeth are shown of the same gage and instead of having all of the individual teeth of the several rows of teeth in staggered relation, this modification shows the teeth of the several rows at one point, as at 26, arranged in a straight line across the end 100 of the feeler tip. The teeth 25 of the modification shown in Fig. 6 are staggered in one direction, while the teeth 25 at the opposite side of the straight row 26 are staggered in the opposite direction.

105 From the above description of the present invention, it will be apparent that by forming the feeler tip of a plurality of separate members, each having a series of horizontal teeth, not only can the series of teeth transversely of the feeler tip be formed of different gage to cooperate with different kinds or characters of filling, but the individual teeth of the several rows of teeth may be staggered in either direction relative to the teeth of an adjacent row thus adapting the same feeler tip for use with various kinds or characters of filling. Indeed, the gage of the several rows of teeth 110 may be widely different, some of which may penetrate the filling employed, while others would not penetrate sufficiently to prevent side swipe movement of the feeler.

115 120 125 130 As will be noted from the description of the present invention, the tip as shown is

formed of three different members or layers, each formed either of the same or different material, and each provided with a row of teeth which are made in the members before the members are assembled, so that the size or gage of the teeth or points, as well as the spacing thereof, may be made of such variety that the feeler tip thus constructed will cooperate more effectively with filling of different counts or degrees of twist than feeler tips having the plain crosswise teeth extending continuously from top to bottom of the feeler.

What is claimed is:

- 15 1. A filling feeler to detect the condition of the filling in the shuttle having a tip provided with a plurality of relatively fixed and closely arranged horizontal rows of filling engaging teeth, the individual teeth of one horizontal row being arranged in a different vertical plane relative to the individual teeth of the adjacent fixed horizontal row to cooperate with different kinds of filling.
- 20 2. A filling feeler to detect the condition of the filling in the shuttle having a tip provided with fixed horizontal rows of teeth of different gage and the teeth of one horizontal row being arranged in different vertical planes relative to the individual teeth of the adjacent row that the teeth of the different horizontal rows and gage may cooperate with different kinds of filling.
- 25 3. A filling feeler to detect the condition of the filling in the shuttle having a tip portion provided with horizontal rows of fixed teeth in which the teeth of one horizontal row are separated a greater distance from each other than are the teeth of another row and are arranged in different vertical planes relative to the teeth of the other row to cooperate with different kinds of filling.
- 30 4. A filling feeler to detect the condition

of the filling in the shuttle having a tip portion provided with horizontal rows of fixed teeth of different gage in which the teeth of one horizontal row are separated a greater distance from each other than are the teeth of another row and are arranged in different vertical planes relative to the teeth of the other row to cooperate with different kinds of filling.

5. A feeler having a tip provided with a plurality of horizontal rows of teeth, the teeth of each row being of different gage from the teeth of an adjacent row to cooperate with different kinds of filling and staggered relatively thereto transversely of the feeler.

6. A feeler provided with a tip formed of a central member having a series of separate filling engaging teeth and secured to the end of the feeler, and upper and lower members each provided with a row of teeth and secured one at each side of the central member with the teeth of the adjacent rows in staggered relation to cooperate with different kinds of filling.

7. A feeler provided with a feeler tip comprising a member having a row of teeth and secured to the end of the feeler and a second member having a row of teeth of different gage secured at one side of the first mentioned member with the teeth of the rows in staggered relation.

8. A feeler provided with a feeler tip comprising a central member having a row of teeth and secured to the end of the feeler and upper and lower members each having a row of teeth and secured one at each side of the central member the teeth of the three members being arranged in staggered relation.

In testimony whereof, I have signed my name to this specification.

HARRY A. DAVIS.
